HORIZONTAL FLUE BOILER WITH BAFFLE
STRUCTURE IN FLUE

George H. Brace, New London, Conn.

Application May 1, 1952, Serial No. 285,473

5 Claims. (Cl. 122—134)

1

This invention relates to improvements in steam generators and water heaters of the type having a boiler enclosing and permitting free circulation of a body of water.

It is the general aim of the invention to provide a steam generator or water heater of simplified construction, which can be easily and economically fabricated and installed and which will operate efficiently for an exceedingly long period and which will require little, if any, maintenance service during its entire life.

Other objects of the invention, as well as features of construction, will become apparent to those skilled in the art from the following description of the annexed drawing, in which:

Fig. 1 is a side elevational view of a steam generator or water heater constructed in accordance with the present invention;

Fig. 2 is a transverse sectional view taken as indicated by line 2—2 in Fig. 1;

Fig. 3 is a longitudinal sectional view of the boiler removed from the firebox and taken as indicated by line 3—3 in Fig. 2;

Fig. 4 is a longitudinal sectional view through the boiler as indicated by line 4—4 in Fig. 2; and

Fig. 5 is an isometric view of the baffle tube and baffles plates utilized in the construction.

In each of the aforescribed figures of the drawing, the reference numeral 10 designates a boiler which is supported in a generally horizontal position upon a firebox 12. A water chamber W is defined within the boiler 10 between the outer cylindrical shell 14 thereof and an inner cylindrical shell 16. The inner shell 16 is longer than the outer shell 14 and, in accordance with the present invention, is supported in eccentric relation to the outer shell by end plates 18, 18 welded or otherwise secured within the ends of the outer shell 14.

A walled opening or passageway 22 between the inner and outer shells is provided on the side of the boiler adjacent the front end thereof to permit the passage of hot gasses to and from the inner shell. The top wall 23 of the passageway is provided by bending the struck portion of the inner shell upwardly and welding the same to the upper marginal edge of the opening in the outer shell. The rear and bottom walls of the passageway 22 are provided by a plate 24 welded to the cut edges of the openings in the inner and outer shells. The front wall of the passageway 22 is provided by an insulating liner 20 on that portion of the front end plate 18 which is adjacent the said passageway.

The passageway 22 is in communication with a flue 26 leading from the fire box 12. As will be

2

noted in Fig. 2, the fire box is lined with a suitable refractory 28, such as fire brick, so that a flame can be introduced therein from a conventional burner 30. The flame and hot gases produced thereby will heat the underside of the outer shell 14 and the hot gases will then pass upwardly in the flue 26 along the side of the boiler toward the passageway 22. The flue has an insulating liner 32, such as asbestos, to a point substantially at the midpoint of the passageway 22. The said passageway is divided by a horizontally disposed plate 34 welded to the rear wall 24 of the passageway and to the shell 36 of the flue. Thus the baffle defines a gas inlet opening 38 so that the inner shell will receive hot gases from the fire box, said gases being introduced in the direction of the arrows in Figs. 1 and 2.

In further accord with the present invention, baffle means are provided within the inner shell 16 to circulate the gases therein to effectively heat said shell and the water chamber W. The baffle means includes a supporting tube 40 secured in concentric relation with the inner shell 16 with its ends abutting the heat insulating liners 42, 42 provided on the inner faces of closure plates 44, 44 located, respectively, on the ends of the inner shell. The tube 40 supports, as by welding to its outer periphery, a baffle 46 which is disposed generally parallel to the axis of the tube and which is inclined outwardly so that the outer edge of said baffle engages the inner edge of the flue baffle plate 34. Preferably, the baffles 34 and 46 are welded along their abutting edges. The baffle 46 extends from the front end of the tube lengthwise thereof beyond the midpoint of the tube. At approximately the center of the tube 40, a transversely disposed plate 48 is welded to the tube and to the underside of baffle 46. As shown in Fig. 2, the transverse baffle 48 extends between the tube and the inner shell of the boiler and is approximately semi-circular in configuration. As will be apparent from the drawing, the baffles 46 and 48 direct the hot gases introduced at the flue inlet opening 38 downwardly and around the tube 40 on the front half thereof. The gases then escape over the free end 50 of the baffle 48 to circulate along the upper portion of the inner shell 16 from end to end. A longitudinally disposed upper baffle 52 is welded to the tube 40 from end to end and extends generally vertically upwardly to engage the inner shell of the boiler. The baffle 52 prevents the gases from passing completely over the tube and instead directs them downwardly at the rear half of the tube as shown in Fig. 4. The gases then pass upwardly and forwardly of the tube as

shown in Fig. 3 toward the passageway 22. That part of the passageway above the baffle 34 is designated by reference numeral 54 and defines a gas outlet opening to the flue which extends upwardly to a stack fitting 56 for the discharge of the flue gases.

From the foregoing description it will be understood that a boiler constructed in accordance with the present invention is adapted to circulate the heating gases internally of the water chamber to efficiently heat the water contained therein. The eccentric arrangement of the shells provides for accelerated heating of the water in the lower portion of the boiler thereby causing water circulation to be quickly instituted. It will also be understood that blower means are unnecessary to effect gas circulation in the described manner. In each of baffles 46, 48 and 52 gas vent openings 58 are provided to permit the escape of gas which might tend to build up in otherwise restricted areas. There is also provided a gas vent tube 60 extending from the top portion of the inner shell 16 through the outer shell 14 into the flue adjacent the stack fitting to permit the escape of gases which might be trapped within the inner shell.

It will be further understood that the boiler of this invention can be economically fabricated by welding the various elements and economy is further served by the elimination of flue pipes etc. which are costly in installation and which require frequent maintenance or replacement.

While one specific embodiment of the invention has been shown and described, it is not the intention to limit the scope of the invention except as indicated by the claims which follow.

I claim:

1. A boiler construction comprising a generally cylindrical outer shell, a pair of end plates closing the ends of said outer shell, a firebox supporting said outer shell in a substantially horizontal position, means defining a gas flue extending from said firebox upwardly along the side of said outer shell, a generally cylindrical inner shell extending substantially horizontally between said end plates in spaced relationship within said outer shell to define a water chamber therebetween, means defining a watertight gas duct between the interior of said inner shell and said flue, a tube extending substantially horizontally between said end plates in spaced relationship within said inner shell, and baffle means extending completely across said flue and through said duct to said tube to separate said duct into a gas inlet passageway on the side of said baffle means adjacent the firebox and a gas outlet passageway on the opposite side of said baffle means whereby flue gases are directed into said inner shell and around said tube and returned to said flue.

2. A boiler construction comprising a generally cylindrical outer shell, a pair of end plates closing the ends of said outer shell, a firebox supporting said outer shell in a substantially horizontal position, means defining a gas flue extending from said firebox upwardly along the side of said outer shell, a generally cylindrical inner shell extending substantially horizontally between said end plates in eccentrically spaced relationship within said outer shell to define a water chamber therebetween with the most restricted portion of said water chamber disposed adjacent said firebox, means defining a watertight gas duct between the interior of said inner shell and said flue, a tube extending sub-

stantially horizontally between said end plates in spaced relationship within said inner shell, and baffle means extending completely across said flue and through said duct to said tube to separate said duct into a gas inlet passageway on the side of said baffle means adjacent the firebox and a gas outlet passageway on the opposite side of said baffle means whereby flue gases are directed into said inner shell and around said tube and returned to said flue.

3. A boiler construction comprising a generally cylindrical outer shell, a pair of end plates closing the ends of said outer shell, a firebox supporting said outer shell in a substantially horizontal position, means defining a gas flue extending from said firebox upwardly along the side of said outer shell adjacent one of said end plates, a generally cylindrical inner shell extending substantially horizontally between said end plates in spaced relationship within said outer shell to define a water chamber therebetween, means defining a watertight gas duct between the interior of said inner shell and said flue, said last mentioned means including a portion of said inner shell bent generally radially outwardly and secured to said outer shell to provide one wall of said duct and said one end plate providing another wall of said duct, a tube extending substantially horizontally between said end plates in spaced relationship within said inner shell, and baffle means extending completely across said flue and through said duct to said tube to separate said duct into a gas inlet passageway on the side of said baffle means adjacent the firebox and a gas outlet passageway on the opposite side of said baffle means whereby flue gases are directed into said inner shell and around said tube and returned to said flue.

4. A boiler construction comprising a generally cylindrical outer shell, a pair of end plates closing the ends of said outer shell, a firebox supporting said outer shell in a substantially horizontal position, means defining a gas flue extending from said firebox upwardly along the side of said outer shell adjacent one of said end plates, a generally cylindrical inner shell extending substantially horizontally between said end plates in spaced relationship within said outer shell to define a water chamber therebetween, means defining a watertight gas duct between the interior of said inner shell and said flue, said last mentioned means including a portion of said inner shell bent generally radially outwardly and secured to said outer shell to provide one wall of said duct and said one end plate providing another wall of said duct, a tube extending substantially horizontally between said end plates in spaced relationship within said inner shell, first baffle means extending completely across said flue and through said duct to said tube to separate said duct into a gas inlet passageway on the side of said baffle means adjacent the firebox and a gas outlet passageway on the opposite side of said baffle means, and second baffle means within said inner shell including a transversely disposed baffle plate extending between said tube and said inner shell and cooperating with said first baffle means to direct hot gases from said inlet passageway downwardly and then upwardly around said tube adjacent said one end plate, and a substantially horizontally disposed baffle plate included in said second baffle means extending between said end plates in spaced relationship to said transverse plate and cooperating therewith to direct the gases from adjacent said one

end plate downwardly and then upwardly around said tube adjacent the other end plate and then into said outlet passageway.

5. A boiler construction comprising a generally cylindrical outer shell, a pair of end plates closing the ends of said outer shell, a firebox supporting said outer shell in a substantially horizontal position, means defining a gas flue extending from said firebox upwardly along the side of said outer shell adjacent one of said end plates, a generally cylindrical inner shell extending substantially horizontally between said end plates in eccentrically spaced relationship within said outer shell to define a water chamber therebetween with the most restricted portion of said water chamber disposed adjacent said firebox, means defining a watertight gas duct between the interior of said inner shell and said flue, said last mentioned means including a portion of said inner shell bent generally radially outwardly and secured to said outer shell to provide one wall of the said duct and said one end plate providing another wall of said duct, a tube extending substantially horizontally between said end plates in spaced relationship within said inner shell, first baffle means extending completely across said flue and through said duct to said tube to separate said duct into a gas inlet passageway on the side of said baffle means adjacent the fire box and a gas outlet passageway on the opposite side of said baffle means, and second baffle means within said inner shell including a transversely disposed baf-

file plate extending between said tube and said inner shell and cooperating with said first baffle means to direct hot gases from said inlet passageway downwardly and then upwardly around said tube adjacent said one end plate, and a substantially horizontally disposed baffle plate included in said second baffle means extending between said end plates in spaced relationship to said transverse plate and cooperating therewith to direct gases from adjacent said one end plate downwardly and then upwardly around said tube adjacent the other end plate and then into said outlet passageway.

GEORGE H. BRACE.
